UNITED STATES PATENT OFFICE.

ISAAC S. CLOUGH, OF BROOKLYN, AND VINCENT FOUNTAIN, JR., OF NORTH SHORE, NEW YORK.

AUTOMATON-DANCER.

Specification forming part of Letters Patent No. 43,759, dated August 9, 1864.

To all whom it may concern:

Be it known that we, I. S. CLOUGH, of Brooklyn, in the county of Kings and State of New York, and VINCENT FOUNTAIN, of North Shore, in the county of Richmond and State aforesaid, have invented a new and Improved Dancing Automaton; and we do hereby declare that the following is a full, clear, and exact description thereof, which will enable any one skilled in the art to make and use the same, reference being had to the accompanying drawing, making a part of this specification.

The drawing represents a perspective view of our invention.

This invention consists in suspending a figure with jointed limbs from an elastic cord stretched between uprights over a suitable platform in such a manner that by touching the cord with the finger the feet of the jointed figure are caused to touch the platform, and if the taps on the cord are repeated in quick succession the figure begins to dance on the platform.

The invention consists also in the employment or use, in combination with the dancing figure, of a metallic disk supported in the center in such a manner that the feet of the jointed figure on striking said disk produce a musical sound, and the value of the toy is thereby enhanced.

A represents a figure of a man or other subject, made of wood or any other suitable material, with jointed legs and arms and painted with bright colors to give to the whole a pleasing appearance. This figure is suspended from an elastic cord, B, which is stretched between two uprights, C, rising from the platform D. The height of the cord above the platform is such that the feet of the figure A nearly touch said platform, and that by touching the cord lightly with the finger the feet of the figure are brought in contact with the plat-

form. By imparting to the cord repeated taps in quick succession the figure A begins to dance on the platform in the most comical manner, and this dancing motion continues as long as the motion of the cord is continued.

In order to enhance the effect of the toy and to give it still greater value, particularly in the hands of children, we have added to the platform D a metallic disk, E, supported by a stud, a, in its center, so that the same, when struck by a stick or hammer, will produce a musical sound. This disk is placed under the feet of the jointed figure at such a distance that the same will not touch it when the cord is at rest; but if by taps on the cord the figure is set in motion its feet strike the disk and a pleasing sound is produced, imitating the music accompanying a real dancer.

The platform D may be embellished in various ways—for instance, a hand, b, may be attached to the stud a, playing over a series of compartments marked off on the platform around the disk, and if suitable words are written in these compartments an entertaining game can be combined with the dancing automaton, and, in order to prove that the dancer is a loyal man, a national flag, F, is attached to the platform D.

What we claim as new, and desire to secure by Letters Patent, is—

Suspending the figure A from an elastic cord, B, stretched between uprights C, over the sounding-disk E, attached to the platform D, so that the motion of the figure is produced by the swaying of the cord and the contact of the feet of the figure with the bell or disk produces a musical sound.

ISAAC S. CLOUGH.
